UNITED STATES PATENT OFFICE.

PETER FRASER, OF HAMILTON, ONTARIO, CANADA.

SPRING BED-BOTTOM.

SPECIFICATION forming part of Letters Patent No. 288,223, dated November 13, 1883.

Application filed November 10, 1882. (No model.)

To all whom it may concern:

Be it known that I, PETER FRASER, of Hamilton, in the county of Wentworth, in the Province of Ontario, Dominion of Canada, have invented certain new and useful Improvements 5 in Spring Bed-Bottoms; and I do hereby declare that the following is a full, clear, and exact description of the construction and operation of the same.

10 The object of the invention is to provide a spring bed-bottom that will be noiseless, rounded or deck-shaped on the top, easy to lie on, very durable, and will give to weight and retain its shape on the removal of the weight, 15 and which can be detached or combined with a bedstead.

My invention consists, first, in constructing the sides and ends of a bed-bottom with a series of staples of a peculiar form driven there- 20 in, leaving a clear space between the wood and staple, the latter retaining the top portion of the spring in such a way that while all the side and end springs are held to the sides and ends of the frame the said springs slide up and 25 down upon the staples, and by making the outside row of side and end springs a little shorter than the inner ones the bed is slightly raised or rounded in the center, like the deck of a ship; second, in constructing, for a slight 30 change, the bed-bottom and bedstead combined in one, in which the bed-bottom is constructed just the same as when detached, only the bed-bottom is a solid fixture, with the sides and ends somewhat more elevated above the 35 staples than when the bed-bottom is separate from the bed, so as to hold a mattress upon the springs, the posts of the bed being affixed to the bed-bottom, with all the springs attached thereto.

40 By reference to the drawings forming part of this specification it will be seen that Figure 1 is a plan view of the bed-bottom. Fig. 2 is a partial section of the same. Fig. 3 is a detached section, showing one spring under pressure. Fig. 4 is a top view of one of the slats, showing cord under the springs. Fig. 5 is a section of combined bedstead and bed-bottom. Fig. 6 shows the end knotted or fastened to the body of the spring. Fig. 7 is a side view 50 of one of the staples. Fig. 8 represents a bed-section with swinging ends, for convenience in transportation.

A A, Fig. 1, represents a frame forming the bed-bottom, and cut thinner at the inner top portion all around, forming a recess, *a*, and a projection, *b*, as shown at the section, Fig. 2. 55

I construct wire staples of the form shown at B, Fig. 7, and drive them into the frame, the lower end into the projection and the upper part into the top of the frame at a slight angle, leaving a space between the inner side 60 of the frame and that portion of the staple not in the wood, and the top coil of each spring C is caught by one of the staples and the corner springs by two staples, as shown at Fig. 2. 65

The bottom of each spring C rests upon the slats D, two pieces of twine, *e*, being laid along each slat under the springs to deaden sound, and they are secured to the said slats by small staples *f* in the usual way. All the springs 70 are connected together by O-shaped links E, which form a very convenient and easy method of securing the springs to one another. The bent ends of the links are simply made to catch on each spring, and bent around it without solder or other devices. 75

The springs on the outside may be a little shorter than the inner ones, so as to always have the center of the bed the highest or deck-shaped, and always retain that shape when 80 there is no weight upon the bed. When weight is on the bed, all the outside rows of springs are pressed down, but retain their upright position, on account of the staples B, which prevents the said springs from being pushed to 85 one side, while all the springs, being connected together by the links E, retain a perpendicular position at all times.

It will be observed that each spring is bent S-shaped, as at *x*, a short distance from its 90 end, which end is simply bent around the S portion without soldering, which makes the spring firm, yet elastic, with no sharp end, which is objectionable, as in some of the old kinds of springs the ends would work loose 95 and penetrate and tear the canvas covering or mattress, sometimes both.

By making the sides and ends A a little higher than shown at Figs. 1 and 2 by a strip, F, Fig. 5, the frame is slightly raised to keep 100 in place a mattress, G, and posts H being affixed to the frame so constructed, a combined bed-bottom and bedstead is formed, which dispenses with a separate bed-bottom when

so required. I also construct the bed-bottom and bedstead in such a manner that it forms a complete bed and lounge, the bed-bottom being made to swing back nearly upright to 5 form the back of the lounge; and for convenience in transportation I also construct the ends of the bed in such a way as to be pivoted to the side frames, A, of the bed-bottom, and fastened with any suitable hook or catch when 10 in use. For shipment the ends will be unhooked and folded over on the bed-bottom, as shown by dotted lines in Fig. 8, which is a section of the swinging end.

Having thus described my device, what I 15 claim as my invention is—

1. A spring bed-bottom constructed, substantially as herein shown and described, with a groove, a, cut around the inner upper sides and ends of the frame A, and having staples 20 B inserted in the frame, each staple inclosing

the top coil of a spring, C, opposite it, by which the outer rows of springs are enabled to slide on said staples and always held thereby in an upright position, as shown, without pressure at Fig. 2 and under pressure at Fig. 3. 25

2. The combination of a bed-bottom and bedstead, when the sides and ends A are provided with staples B, and the outer rows of springs C sliding in and held in an upright position by the said staples, substantially as herein set 30 forth.

3. The combination, with the bed-bottom A, as constructed, of the swinging ends of a bed, as shown at Fig. 8, for the purpose specified.

Dated at Hamilton, Canada, this 13th day 35 of October, 1882.

PETER FRASER.

In presence of—

W. BRUCE,
T. COCKBURN.
